THREE-DIMENSIONAL GAME BOARD

Thomas D. Ledgerwood, 823 Mockingbird Lane,
Norman, Okla. 73069

Filed Dec. 1, 1971, Ser. No. 203,933

Term of patent 14 years

Int. Cl. D21—01

U.S. Cl. D34—5 SS

FIG. 1 is a perspective view of the three-dimensional game board;

FIG. 2 is one side elevational view thereof;

FIG. 3 the opposite side elevational view thereof; and

FIG. 4 is a top view of the novel design.

I claim:

The ornamental design for a three-dimensional game board, as shown.
